CLAIM

The ornamental design for a display screen with transitional graphical user interface, as shown and described.

DESCRIPTION

FIG. 1 is a front view of a first image of a first embodiment of a display screen with transitional graphical user interface showing our new design;

FIG. 2 is a front view of a second image of a first embodiment showing our new design; and,

FIG. 3 is a front view of a third image of a first embodiment showing our new design.

The subject matter in this patent includes a process or period in which an image changes into another image. This process or period forms no part of the claimed design.
